UNITED STATES PATENT OFFICE.

SELDEN G. NORTH, OF PHILADELPHIA, PENNSYLVANIA, ASSIGNOR TO
NORTH BROTHERS MANUFACTURING COMPANY, OF PHILADELPHIA,
PENNSYLVANIA, A CORPORATION OF PENNSYLVANIA.

REMOVABLE-BLADE SCREW-DRIVER.

No. 842,107.

Specification of Letters Patent.

Patented Jan. 22, 1907.

Application filed January 8, 1906. Serial No. 295,109.

To all whom it may concern:

Be it known that I, SELDEN G. NORTH, a citizen of the United States, residing in Philadelphia, Pennsylvania, have invented certain Improvements in Removable-Blade Screw-Drivers, of which the following is a specification.

The object of my invention is to provide a screw-driver or other similar tool with a removable blade or point, so that a blade of one size can be readily removed and another blade of different size substituted for it, or in the case of a blade breaking said blade can be discarded and another blade substituted for it. This object I attain in the following manner, reference being had to the accompanying drawings, in which—

Figure 1 is a view of a screw-driver illustrating my invention. Fig. 2 is an enlarged view of the lower portion of the screw-driver. Fig. 3 is a section on the line 3 3, Fig. 2. Fig. 4 is a section on the line 4 4, Fig. 3. Fig. 5 is a section on the line 5 5, Fig. 3. Fig. 6 is a sectional view similar to Fig. 4 without the blade. Figs. 7 and 8 are detached views of the blade. Fig. 9 is a view showing my invention applied to the screw-driver bit, and Fig. 10 is a view of a modification of my invention.

It is desirable in making a screw-driver to provide a number of blades which can be attached to the shank of the screw-driver, these blades being of different widths, so as to accurately fit the grooves of different-sized screws. Further, it is desirable to have a screw-driver in which the blades or points can be renewed. A great objection to the average removable-point screw-driver at present on the market is the fact that it is cumbersome, and a clamp or chuck must be provided for securing the blade to the shank of the screw-driver. By my invention, however, there are only two parts, the blade and the shank, the blade being held in the shank by friction, as fully described hereinafter.

A is the shank of the screw-driver, having a handle B, and I may form a magazine b in the end of the handle, as shown by dotted lines, to hold the series of blades belonging to the screw-driver.

The screw-driver may be of the ratchet type or may be a plain screw-driver without departing from my invention.

D is the detachable blade or point, made as clearly shown in Figs. 7 and 8. The end of the shank A is slotted at a, as clearly shown in Fig. 6, and slotted at a' a' at each side, leaving a central web a², which extends nearly to the end of the shank A. The blade D is forked, as shown, forming two prongs d d, which are shaped to fit the slots a' in the shank A, the body portion d' of the blade fitting the transverse slot a. The end d² of the blade is shaped to fit the groove in the head of the screw. The slots a' a' are of such a width that the blade will neatly fit therein.

In order to retain the blade in position, I bend the forks d d of the blade, as clearly shown in Fig. 8, so that one will be out of line with the other, and there is sufficient spring in the metal so that when the forks of the blade are forced into the slots of the screw-driver they will straighten out and there will be sufficient friction to prevent the accidental displacement of the blade, so that in ordinary work the blade will remain firmly attached to the shank, but the blade can be readily withdrawn by a lengthwise pull.

By this arrangement I am enabled to make a screw-driver blade which can be readily detached from the shank of the screw-driver and which when in position will be rigidly held, there being no cumbersome chucks or clamps for securing the blade to the shank.

As mentioned above, the blades can be of different widths and the blades can be contained in the magazine in the handle, if desired.

In Fig. 9 I have shown a bit A' having a portion which is adapted to fit a brace and slotted to receive the detachable blade D'.

In Fig. 10 I have shown a modification of my invention in which the slots in the shank of the screw-driver A² are cut at an angle one in respect to the other and a flat blade used, so that when the blade is forced into the slots in the shank the forked portions will follow their respective slots and be bent out of line, the forks being sufficient to hold the blades in proper position.

It will be seen also that I make a very strong shank, as I extend the web a² to a point near the end of the shank, thus rigidly connecting the two sides of the shank which are separated by the forks of the blade.

It will be understood that while I have described my invention in connection with a screw-driver it may be used in connection with a chisel or a carving-tool, and, in fact, in connection with any tool in which it is desired to fit a detachable blade to a shank or body portion.

I claim—

1. The combination in a tool, of a shank 10 grooved at each side leaving a central web, a flat blade forked at the inner end, the forked portions of the blade being out of line with the grooves in the shank so that the blade when forced into the shank will be held to the shank by friction, substantially as described.

2. The combination in a tool, of a shank 15 grooved at each side leaving a central web, a detachable blade forked at the inner end, the forked portions being bent one out of line 20 with the other so that the blade will be held

to the shank by friction, substantially as described.

3. The combination in a tool, of a shank having a transverse slot at the end and grooved at each side leaving a central web ²⁵ uniting the two portions of the shank, a blade having forks at one end; said forked portions adapted to the grooves in the sides of the shank, the body portion of the blade being adapted to the transverse slot in the ³⁰ end of the shank, the two forks being bent one out of line with the other, substantially as described.

In testimony whereof I have signed my name to this specification in the presence of ³⁵ two subscribing witnesses.

SELDEN G. NORTH.
